ABSTRACT OF THE DISCLOSURE

A papermaking machine shaping cylinder which includes a plurality of trapezoidal-shaped trough-like boxes at the periphery which are open to a wire mesh circumferentially disposed on the cylinder over the boxes. The boxes are connected by rings to twin wheels spaced apart from one another, and which are themselves connected to the shaft of the cylinder. Two distributor members are urged against openings in the rings so as to communicate either compressed air or vacuum to the interior of the boxes in a fashion to adhere fibers from a slurry onto the wire mesh and then to transfer the formed fibrous sheet onto a felt contacting the cylinder. A screw-threaded bush mounted on two aligned pins allows a displaceable segment of the cylinder periphery to move toward and away from the shaft to facilitate assembly and disassembly of the mesh.

This invention relates to an improvement in the shaping cylinders for the continuous machines used in the manufacture of paper, paperboards, nonwoven fabrics, asbestos-cement and the like.

As is known, the machines of the "continuous" type for paper manufacture comprise one or more manufacturing units, comprising a container to hold a suspension of fibres in water, and a hollow cylinder, which is partially dipped in the suspension and coated by a wire mesh or the like and is rotated about a horizontal axis. The water in the container oozes through the meshes of the wire gauze or net, whereas the fibres stick thereto to form a thin layer. Such a layer, as it reaches the top of the cylinder, adheres to the lower surface of a collecting felt arranged tangentially with respect to said cylinder and adhering to a portion thereof, thrust thereagainst by a pressing or setting roller.

In the case of a machine having a plurality of manufacturing units, there is a succession of paper layers, called "castings" which are superposed in said collecting felt until reaching the expected thickness.

It is apparent that in machines of the kind referred to above in order that adhesion of the sheet to the lower surface of the collecting felt may be achieved, the sheet should exhibit no discontinuity, especially in a direction which is transversal to the drum.

An object of the invention is to provide a shaping cylinder by means of which it is possible to manufacture a continuous paper layer cut according to scripts, figures or drawings whatsoever. Such a cut layer can be incorporated between two continuous layers, either of the same or of different colors, so as to obtain a "watermark" paper which can be of a color other than that of the sheet, or can be applied on a continuous layer, either alone or in combination with other cutout layers so as to obtain an end product composed by paper (or paperboard) reproducing the desired figures or symbols, in one or more colors.

According to the invention a device is provided, which consists, in combination, of a horizontal shaft carrying

2

at least two wheels staggered and integral with said shaft, at least two ring gears having radial openings affixed to the periphery thereof, a set of boxlike compartments having a trapezoidal cross-sectional shape and arrayed the one alongside the others and integral with said ring gears, and arranged along the generating lines of the cylinder, with the larger base open and wrapped by a wire mesh, and the lesser base closed, a pair of holes formed at the ends of each boxlike compartment in registry with the openings of said rings, and a pair of fixed distributors which slide in a seal-tight manner against the inner edge of said rings, so as to establish an air pressure or a negative pressure in the interior of said boxlike compartments, as a function of their position during the rotation of the cylinder.

Said distributors consist of two shoes in the form of arcs of a circle, having a set of radial chambers and supported by a rocker mounted idly on the cylinder shaft.

Still according to the invention, said radial chambers are formed, each, by a fitting for a duct which opens into a source of compressed air or of negative pressure, according to the position of the shoes aforementioned so as to cause the sheet fibres to adhere to said wire mesh and to cause the sheet to be released from the mesh, the result being the adhesion of the sheet to the collecting felt.

Still according to the invention, one or more portions of the wire mesh are coated with a varnish or the like, according to a preselected pattern, to prevent the formation of the fiber layer in that portion or portions so as to obtain a "cut-out" sheet according to the preselected patterns.

This invention will now be described with reference to the accompanying drawings which show, by way of illustration without limitation, a preferred embodiment of the invention.

In the drawings:

FIG. 1 is a front elevational view of the device, partly in section, along a plane perpendicular to the axis of rotation.

FIG. 2 is a side elevational view, in section along the vertical plane passing through the axis of rotation.

FIG. 3 shows the detail of the removable sector.

FIGS. 4 and 5 shows the cross-sectional views, taken along the planes A—A and B—B of FIG. 3.

Referring to FIGS. 1 and 2, the numeral 1 indicates the horizontal shaft, mounted for rotation in journals (not shown), which receives its rotary drive from any drive-transferring mechanism, or is directly driven by the collecting felt. The shaft 1 dips in a manufacturing unit or tub containing a suspension of fibres in water whose outer level is shown at 2 in FIG. 1 whereas 2' is indicative of the inner level.

To the shaft 1 are keyed two twin wheels 3, appropriately spaced apart from one another, to which are affixed by screws 4 the circular rings 5 equipped with a set of radial openings 6 and integral with the front circle 7 having a rim 8. To the rings 5 are affixed the boxes 9 having a trapezoidal cross-section, which are arranged according to the generating lines of the cylinder and mounted on said rings by the screws 10 and 11 (FIG. 5). The boxes 9 are placed the one alongside the others (see also FIG. 3), and comprise the two sidewalls 12, the bottom wall 13 and the transversal sheet metal walls 14 whose outline is slightly arcuate. The boxes 9 are open at their tops and a mesh 15, formed by a wire mesh or another mesh of an appropriate material, is mounted taut thereon.

On the inner edge of the rings 5 are mounted two distributor members 16 in the form of a fixed shoe, having an angular width of a preselected amplitude. Each distributor 16 is supported by a rocker 17 having a hub 18

mounted idly on the shaft 1 and is resiliently urged against said edge of the foraminous ring 5 by springs 19 located about the guiding posts 20.

The two arcuately shaped distributors 16 comprise segments 21 having sealing gaskets 22, between said segments a set of radial chambers 23 being formed, which communicate via first openings 23' with the openings 6 of the ring 5 and thus with the interior of the boxes or tubs 9 through the openings 35. The radial chambers 23 of the distributor 16 have a second opening or fitting 24 for the connection with a source of compressed air or a vacuum source, as will be more detailedly set out hereinafter and as shown in FIG. 1.

Over the wire mesh 15, a continuous collecting felt 25 is caused to slide tangentially and is pressed against the cylinder by a pressure roller 26.

In order to facilitate the assembling and disassembling operations of the mesh 15, the wheels 3 have a sector 27 which can be displaced towards the centre of the cylinder by the agency of the screw-threaded bush 28 which is active against the pins 29. In order that such a displacement may be allowed (FIGS. 3 and 4) the set of boxes 9 encompassed by said sector have at their sides two sets of pins 30 carrying the tongues 31 aligned with the blades 14. The pins 30 are carried by the strips 32 having set screws 33. As seen in FIG. 4, the pins 30, as regards the portion concerning the ring 5, are directly screwed on the same ring. Alternatively, any appropriate sealing connecting means may be utilized here.

The operation is as follows. Assuming that the directions of rotation are those of the arrows of FIG. 1, a negative pressure is applied to the chambers 23 of the distributor 16 which are located between the immersed portion of the cylinder and the point of contact between the roller 26 and the felt 25, whereas compressed air is fed to the chambers 23 lying beyond said point of contact. The result is that the fibres contained in the suspension 2 adhere to the wire mesh 15 down to the underside of the roller 26, whereupon, as this point has been overtaken, the sheet formed by said fibres is urged by the effect of compressed air so as to adhere to the lower face of the collecting felt 25 with which it goes on towards the further processing operations.

If one or more areas, shaped according to any pre-selected areas in the shape of any pattern or inscription, are clogged or waterproofed on the wire mesh 15 by means of a varnish or any other suitable means, no sheet formation takes place in said areas, so that a continuous "cutout" sheet is obtained, which is empty in said areas and is separated from the mesh 15 and adheres to the lower face of the felt 25 by virtue of the action of the compressed air which, from the chamber 23, passing through the openings 6 of the ring, reaches the interior of the boxes 9 as the latter pass over the distributor 16. To regulate the action of the negative and the positive pressures in the distributor 16, the latter can be rotated about the shaft 1, either manually or by any other control member (not shown).

To do away with fibres which may possibly have adhered to the clogged areas of the wire mesh 15, water sprays are provided, emerging from one or more sprinklers 34.

With a cylinder such as described above, it is possible to operate at a speed which is definitely higher with any kind of manufacturing unit.

Of course, with a unidirectional manufacturing unit which already permits of high speeds, said speeds can obviously be doubled, well felted sheets being always the result. In addition, as compared with a conventional cylinder, it is possible to obtain much higher thicknesses, so that the cylinder according to the invention lends itself in a special manner for continuous machines for the production of paperboards or Bristol boards.

With more than one cylinder, as described above, or with a conventional cylinder and a plurality of cylinders or the kind described herein, applied to a continuous

papermaking machine, a wide variety of special papers can be manufactured as a continuous sheet, a result which cannot be achieved with the usual machinery.

With a continuous machine having two manufacturing units, the first of which has a conventional shaping cylinder and the following unit has a shaping cylinder with sucking and blowing boxes, a special composite paper can be manufactured, since on the first shaping cylinder (either conventional or special) which forms a continuous sheet of the width of said cylinder, the sheet in question can be printed during the lamination with scripts or patterns which have been formed, either as a positive or negative image, on the mesh of the special cylinder.

If the "cutout" sheet made by the special cylinder has a colour other than that of the sheet formed by the first cylinder, after the lamination a single sheet of paper is obtained, which has faces of different color but reproduces in one color only the letters, numerals or patterns reproduced on the mesh of the second shaping cylinder.

With a machine equipped with a conventional shaping cylinder and a cylinder according to this invention, it is possible to manufacture continuously blank envelopes already fitted with linings of a different color, by applying breaking lines on the first sheet which delimits the shape of the envelope and obtaining the pattern of the lining as a positive image, so that the latter, upon lamination, with an appropriate synchronization of the two shaping cylinders, may go to be united in the exact position where the lining should be in an envelope.

With a machine having three manufacturing units, the first and the third of which are equipped with conventional cylinders whereas the second, which is at the center, has a sucking and blowing cylinder, by causing the central cylinder to reproduce patterns of a color other than those of the other two sheets, it is possible to obtain, upon lamination, a single sheet with internal scripts or patterns of a different colour. These papers are extremely useful for safety purposes, as it generally occurs with papers for banknotes and the like.

If in the subject machine the gauze is punched to obtain a watermark and the punched portion is delimited by a varnish, one obtains, upon lamination, a sheet of paper which internally contains a water-mark whose color can be other than that of the remainder of the sheet.

Such a result could be obtained heretofore only by manual procedures: by the present invention this can be obtained as a continuous operation, so that a craftsman-like work can now be effected on an industrial scale.

If the machine, instead of a single sucking and blowing cylinder has two of them, that is the second and the third, both synchronized with one another, it would be possible to obtain on the second cylinder the punching delimited by a varnish whereas the third could have varnished only the portion occupied by the punching in the second cylinder, so that, upon lamination, there is a sheet of paper which can be, by providing three batches of different colors, of a single color on a surface, whereas the other surface has another color, a third color being provided by the watermark which coincided, on account of the synchronization, with the empty space provided in the third shaping cylinder.

If the machine had three shaping cylinders, all three of the sucking and blowing type so that in the two lateral shaping cylinders the non-formation of the sheet is caused to coincide, the result would be a single watermarked sheet which could have, by properly coloring the batches, the watermarked sheet with a color different from that of the remainder of the sheet, well visible on the two surfaces.

Finally, by resorting to the already illustrated principle, with a continuous machine having as many manufacturing units as the color one desires to reproduce, on the first sheet, formed also by a conventional shaping cylinder, it is possible to laminate fragments of sheets of

different color which could be properly selected so as to reproduce any multicolored pattern.

This invention has been described with reference to a preferred embodiment, being it understood that modifications and changes can be introduced therein without departing from the scope of the subject invention.

The embodiments of the invention in which an exclusive property or privilege is claimed are defined as follows:

1. A shaping cylinder for machines for manufacturing paper products, comprising: a horizontal shaft; two wheels carried on said shaft and spaced apart from each other, each wheel having an arcuate displaceable segment radially movable toward and away from said shaft; two rings having radial openings fixed to the periphery of said wheels; a plurality of open trough-like members, having a trapezoidal cross section with the larger base open and smaller base closed, disposed one adjacent another on the circumference of and along the lines of generation of said cylinder, said trough-like members being connected at opposite ends to said rings; sealing means connecting a first group of said plurality of trough-like members disposed on said displaceable segment to the remaining plurality of trough-like members disposed on said cylinder; an opening defined in each end portion of said trough-like members in registry with said radial openings in said rings; a wire mesh circumferentially disposed on said cylinder over the open bases of said trough-like members; moving means for moving each said displaceable segment toward and away from said shaft to facilitate assembly and disassembly of said mesh on said cylinder; two arcuately shaped distributor members; means for mounting said distributor members in sealed sliding contact with the inner surface of said rings; a plurality of generally radial passageways formed in said distributor members, each of said passageways having first and second openings, said first openings being in

registry with corresponding ones of said radial openings; and supply means supplying positive and negative air pressures to said passageways, said supply means being disposed in registry with said second openings.

2. A cylinder according to claim 1, wherein said movable means comprises a screw-threaded bush mounted on two aligned pins carried by said displaceable segment and a hub idly mounted on said shaft, respectively, to control displacement of said displaceable segment toward and away from said shaft.

3. A cylinder according to claim 1, further comprising a series of transversal blades carried by said plurality of trough-like members, said blades having an arcuate shape corresponding to the curvature of said cylinder wherein said mesh rests on said blades.

4. A cylinder according to claim 3, wherein said sealing means comprises two longitudinal strips having sealed gaskets.

5. A cylinder according to claim 4, wherein said longitudinal connection strips include a set of pins having, at their upper ends, tongues which are aligned with said blades.
